UNITED STATES PATENT OFFICE.

BERNHARDT C. BERG, OF LOS ANGELES, CALIFORNIA.

OIL BURNER.

Application filed March 19, 1923. Serial No. 626,105.

To all whom it may concern:

Be it known that I, BERNHARDT C. BERG, a citizen of the United States, residing in Los Angeles, in the county of Los Angeles 5 and State of California, have invented certain new and useful Improvements in Oil Burners, of which the following is a specification.

The purpose of my invention is to provide a burner for burning crude or fuel oil, kerosene, distillate or the like, and atomizing the same by steam generated within the device itself instead of atomizing by means of compressed air furnished by an air compressor, or by steam furnished by a boiler. A further object of my invention is to not only generate the steam required to atomize the liquid fuel, but to superheat the steam so generated; dry or superheated steam 20 being of importance in any oil burner, and an essential if intermittent working of the burner is to be obviated.

Other objects of my invention are to provide a means for automatically re-lighting the flame in case it should go out, and to provide a burner which is simple, durable and one in which any tendency to clog is readily overcome. I attain these objects by the mechanism illustrated in the accompanying drawings, in which:—

Figure 1 is a side elevation. Figure 2 is a front elevation. Figure 3 is a top plan view with the atomizer removed. Figure 4 is a detail top plan of the ignition pan. Figure 5 is a side elevation of the atomizer. Figure 6 is a top plan view of the atomizer. Figure 7 is a vertical central section of the atomizer taken on the line 1—1 in Figure 6. Figure 8 is a detail side elevation of the clean-out plunger. Figure 9 is a side elevation showing the automatic re-lighter attached. Figure 10 is a detail top plan of the re-lighter. Figure 11 is a vertical central section of the re-lighter taken on the line 2—2 of Figure 10. Figure 12 is an end elevation of the re-lighter. Similar numbers refer to similar parts in the several views.

The construction of my device is as follows: 11 is a base or ignition pan which is preferably a shallow casting having an open top and side walls 10, strengthened by the ribs 12; the said ribs having slots 13 so that the liquid fuel used for priming or ignition 55 may readily flow to all parts of the pan 11. The pan 11 may be of any desired shape or

size, but is preferably constructed as shown. In an approximately central position in said pan is a raised boss 14 adapted to form a support for the base 15 of the steam generator 16, the latter being secured to the boss 14 by the screw 17. It is obvious that the pan 11 and the steam generator 16 could be made integral if desired, but the construction shown is preferred as being more suitable both as regards manufacture, and for ease of renewal if the same should become necessary. The steam generator 16 is a hollow, table-like casting of rectangular shape in its rearward portion, and semi-circular in its forward portion; the said forward portion having a semi-circular lip 18 which flares outwardly beyond the body of the generator 16. In an approximately central position on the bottom of the steam generator 16 is a downwardly projecting boss or base 15, which is adapted to fit the similar raised boss 14 of the ignition pan 11. The boss 15 has a cored passage 19 connecting with the hollow core or chamber 20 of the generator 16. Connected with the passage 19 is the water supply pipe 21 which may be provided with a union connection 22 and a water regulating valve 23. At the rear end of the steam generator 16 and connected with its chamber 20 is a drain cock 24. Near the rear end of the steam generator 16, at the top and at one side of same is a pipe 25 which connects the chamber 20 with the superheating chamber 26. Located in a 90 symmetrically opposite position on the top of the steam generator 16 is a supporting boss 27 which, together with the pipe 25 serve to firmly support the superheater 26. The superheater 26 consists of a shallow, 95 hollow casting of approximately horse-shoe shape with closed rear end. It is so positioned by its supporting pipe 25 and boss 27, above the steam generator 16, as to project somewhat back of the said generator. Its 100 forward semi-circular end is located back of the lip 18, and its annular cross-section is inclined forwardly and downwardly to the vertical axis of the generator 16. The outer sides of the superheater 26 are also somewhat inclined, the outer width of the superheater being less across the top than across the base. The purpose of these locations and shapes will be more fully hereinafter described. At the rear of the superheater 26, 110 on its upper surface and on its longitudinal axis is a boss 28 adapted to receive a pipe

29 which serves to support the atomizer 30 and to connect the superheater 26 with the steam chamber 31 of the said atomizer 30.

The atomizer 30 consists of an integral casting in which 31 is a steam chamber connected to the superheater 26 by the pipe 29, and having at its forward end a steam nozzle 33. 34 is a fuel chamber connected with a source of fuel supply by the pipe 35 and having a fuel nozzle 36 downwardly inclined to the axis of the steam nozzle 33 and having its opening close to and just above the said steam nozzle. The fuel supply pipe 35 is provided with a fuel control valve 32. 37 is a plunger consisting of a pointed rod adapted to be reciprocated in the steam chamber 31 and into and through the steam nozzle 33 in case the latter should become clogged in any way. Leakage of steam 20 around the plunger 37 is prevented by the gland 38.

The construction of the re-lighting device, shown in Figures 9 to 12 inclusive, is as follows: In place of the pipe 29 the atomizer 30 is connected to the superheater 26 by the bent pipe 40, the elbow 41 and the pipe 42. The base 43 of the re-lighter 45 is mounted on the pipe 40 being secured thereto by the set screw 44. The re-lighter consists of a base 43 having integral with it a cup 45 adapted to contain asbestos wicking 46, or other suitable absorbent and non-inflammable material. Screwed into the cup 45 is a stud 47, flattened at its upper end and vertically adjustable by means of the screw thread on its lower end, so that it may be raised to intercept the lower line of the spray from the atomizer as indicated by the line 51. A short tube 48 is secured to the boss 28 by the screw 49 and serves to protect the flame or spray from the atomizer from cross drafts.

The operation of my device is as follows: All of the parts having been assembled as hereinbefore described; the pipe 21 is connected with a water supply from a pressure system or from an elevated tank, and the pipe 35 connected with a fuel supply. The pet cock 24 and the water valve 23 are then opened and allowed to remain open until the water drips from the pet cock 24, when both the water valve 23 and the pet cock 24 are closed. Liquid fuel is then poured into the ignition pan 11 and lighted. If desired, papers or other combustible material may also be placed in the pan 11, but this is not essential. The plunger 37 is drawn back out of the steam nozzle 33, being held in position by the friction of the gland 38. The heat from the burning fuel in the pan 11 boils the water in the steam generator 16, converting the same into steam which rises through the superheater 26 into the atomizer 30 and issues from the steam nozzle 33. The fuel supply valve 32 is then opened as is also the

water valve 23. The liquid fuel flows down from the fuel nozzle 36 onto the stream of steam blowing out of the steam nozzle 33 and is atomized or blown into a spray. This spray, on account of the inclination of the atomizer 30 is directed downwardly at an angle until it strikes the flat upper surface of the steam generator 16, first passing through the central opening of the superheater 26. The flame from the burning fuel in the ignition pan 11 ignites the spray of fuel and steam, produces a conical flame which on striking the flat upper surface of the steam generator 16 flattens into a fan-shaped flame shooting out between the top of the said steam generator and the underside of the superheater 26, the lip 18 serving to determine the shape and direction of the flame as it leaves the burner. The shape of the lip 18 may be made of various contours to more suitably adapt the shape of the flame to the various purposes for which the burner may be used, or to the different types of fire-boxes. The fuel in the ignition pan 11 burns itself out but the steam is now generated by the flame from the atomizer 30 against the steam generator 16, and as the steam rises through the superheater 26 it becomes superheated before passing up into the atomizer 30. This is of great advantage in operation, as dry steam insures a steadier fire than could be obtained from the use of wet steam. The amount or intensity of flame and heat may be regulated by the water valve 23 and the fuel valve 32. In case the steam nozzle should become clogged from any cause, the plunger 37 is reciprocated by hand in and out of the said steam nozzle, thus clearing the same of any obstruction. The purpose of the reduced width of the top of the superheater as compared with its base is to cause the flame rising about it to cling to its sides closer than it would if the sides were perpendicular. The automatic re-lighter is used where the burner is used in the open air or where it is subject to heavy cross drafts of air. The re-lighter 45 is filled with material such as asbestos wicking and is so adjusted longitudinally on the pipe 40 and its interceptor 47 so adjusted as to height that the said adjuster projects upwardly until it intercepts the spray as indicated by the line 51. This intercepts a small quantity of fuel so that the wicking 46 is saturated and burns constantly thus, in case the flame should be extinguished providing a pilot light which automatically re-lights the spray. The tube 48 is designed to shield or protect the flame from heavy drafts which would tend to divert it from the direction indicated by the lines 50 and 51. The use of the re-lighter is not essential but under many conditions it is of great advantage and improves the working of the burner.

It is obvious that many changes and modifications may be made in my invention, such as making a part or all of the members integral, or modifying the shape of the various parts; all of such modifications being made without departing from the true spirit of my invention.

What I claim as my invention and desire to secure by Letters Patent is:—

- 10 1. An oil burner, including an atomizing member, there being means joined with said atomizing member for generating and superheating steam for use in said atomizing member; said means comprising a hollow steam generating chamber beneath and relatively inclined to the axis of said atomizing member; a hollow, annular superheating chamber relatively spaced above said steam generating chamber, having said 15 atomizing member mounted thereon; and steam connections between said steam generating chamber, said superheating chamber and said atomizing member.
- 20 2. An oil burner, including an atomizing member, there being means joined with said atomizing member for generating and superheating steam for use in said atomizing member; said means comprising a hollow steam generating chamber beneath and relatively inclined to the axis of said atomizing member; a hollow, annular superheat-

ing chamber relatively spaced above said steam generating chamber and having said atomizing member mounted thereon; means likewise being provided for the supply and regulation of liquid fuel and water to said atomizing member and said steam generating chamber respectively, and means for the conveyance of steam from said steam generating chamber to said superheating chamber and from said superheating chamber to said atomizing member.

3. An oil burner, including an atomizing member and means for re-lighting the spray from said atomizing member, said means comprising a cup adjustably mounted relatively below and in front of said atomizing member, said cup being provided with absorbent and non-inflammable material; an intercepting member adjustably mounted on said cup and adapted to be raised into the path of the spray from said atomizing member; likewise means for protecting the flame from said atomizing member, said means comprising a tubular member so located in front of the said atomizing member as to enclose the flame from said atomizing member.
